UNITED STATES PATENT OFFICE.

SIGMUND M. ROSIN, OF PHILADELPHIA, PENNSYLVANIA.

DESIGN FOR A NAPKIN-RING.

SPECIFICATION forming part of Design No. 31,850, dated November 21, 1899.

Application filed October 25, 1899. Serial No. 734,781. Term of patent 3½ years.

To all whom it may concern:

Be it known that I, SIGMUND M. ROSIN, a citizen of the United States, residing in the city and county of Philadelphia, State of Pennsylvania, have invented a new and original Design for a Napkin-Ring, of which the following is a specification, reference being had to the accompanying drawings, forming part thereof.

The leading feature of my design for a napkin-ring is a body having an arched top and a slotted base, presenting together the appearance of a section of a sea-shell.

Figure 1 represents a perspective view of a napkin-ring embodying my design. Fig. 2 represents a vertical section thereof.

In the drawings, A designates the body of a napkin-ring, the same having an arched top B and slotted base C, presenting together the appearance of a section of a sea-shell.

Having thus described my invention, what I claim as new, and desire to secure by Letters Patent, is—

The design for a napkin-ring substantially as shown and described.

SIGMUND M. ROSIN.
